UNITED STATES PATENT OFFICE

WILLIAM C. HIERING, OF NEWARK, NEW JERSEY, ASSIGNOR TO J. E. MERGOTT COMPANY, OF NEWARK, NEW JERSEY, A CORPORATION OF DELAWARE

HAND BAG

Application filed January 30, 1932. Serial No. 589,844.

This invention relates to hand bags, and more particularly to hand bag frames and means for attaching covering material to such frames.

5 Hand bags are extensively manufactured with metal frames to which the covering material, such as leather or cloth, is attached. It has generally been the custom to sew the covering material to the frame; but it has 10 been found that the manufacture of hand bags can be facilitated, at the same time, improving the appearance, by attaching the covering material to the frame by means other than sewing. However, such means as 15 heretofore been employed are objectionable in that they do not satisfactorily compensate for the bunching of the covering material at the corners of the frame, with the result that 20 at the corners the covering material is insecurely attached and has an unfinished appearance.

It is an object of this invention to provide a hand bag having a frame to which the bag covering material may be easily, securely and neatly attached by means of a 25 novel clamping means.

A further object is the provision of a channelled hand bag frame to which the covering means may be securely clamped, and having 30 novel means to compensate for the bunching of the material at the corners of frame, especially when the corners are curved.

These and other advantageous objects, which will later appear, are accomplished by 35 the simple and practical construction and arrangement of parts hereinafter described and exhibited in the accompanying drawing, forming part hereof, and in which:

Figure 1 is a perspective view of a hand 40 bag embodying the invention.

Figure 2 is a perspective view of a frame made in accordance with the invention, the frame having a curved corner;

Figure 3 is a perspective view of holding 45 plate designed for use with a frame having curved corners as shown in Figure 2.

Figure 4 is a perspective view of a frame member as shown in Figure 2, showing in detail the manner in which the holding plate 50 shown in Figure 3 is used.

Figure 5 is a perspective view of a corner of the frame member having covering material attached thereto, and

Figure 6 is a sectional view of the frame member taken on line 6—6 of Figure 4,

Figure 7 is a fragmentary perspective view of the curved corner of a frame provided with a modified form of holding plate,

Figure 8 is a fragmentary perspective view of the modified form of holding plate shown in Fig. 7, provided, at its outer ends, with lugs designed to be passed through the adjacent apertures in the upwardly bent portion of the bottom flange of the frame member,

Figure 9 is a fragmentary perspective view of the curved corner of a frame member provided with a modified form of holding plate, and

Figure 10 is a fragmentary perspective view of the modified form of holding plate shown in Fig. 9, which is provided at its outer ends with lips designed to be snapped over the upwardly bent portion of the bottom flange of the frame member as shown in Fig. 9.

Referring to the drawing in Figure 1 is shown a hand bag having a pair of similar channelled U-shaped frame members hingedly connected. Each frame member is made from a suitable blank of material bent to present, in cross-section, an outwardly disposed channel having an inner side wall 15 provided with top and bottom flanges 16, 17 directed outwardly at right angles thereto, the top flange 16 having a flange 18 bent at right angles thereto and directed towards the bottom flange 17, the flange 18 being parallel to the inner wall 15.

The bottom flange 17 is wider than the top flange 16, and has a portion 19 which may be bent upwardly (see Fig. 2) to provide an outer side wall parallel with the inner wall 15, the portion 19 being provided with a plurality of apertures 20, which enable it to be easily bent upwardly.

As shown in Figure 5, the covering material 21 is doubled and inserted in the channel formed by the wall 15, and the flanges 16, 17, 18; after which the portion 19 of flange 17 is bent upwardly to securely clamp

the covering material to the frame member.

At the corners of the frame the flange 17 is provided with no portion 19, and when the corners are curved as shown in the drawing, provision must be made for the bunching of the covering material. This is accomplished by covering the material at the corners with a flat plate 22, curved to coincide with the corner, the plate having apertures 23 at its ends by means of which it is secured by rivets 24 to the adjacent portions 19 of the flange 17, as shown in Figure 4, said portion 19 being provided with elongated slots 23' for the reception of the rivets 24 carried by the plate 22. The rivets 24, after being passed through the slots 23' are upset, as shown in Figure 6, the slots 23' being preferably elongated, as shown in Figure 2, to allow the rivets 24 to have limited sliding engagement therein for adjusting purposes (see Fig. 4).

It is clear that the plate 22 will crowd the covering material into the space between wall 15 and flanges 16 and 18, so that the outward appearance of the covering material is smooth and finished at the corners.

The form of holding plate shown in Figure 8 is provided, at its outer ends, with lugs 25 adapted to be passed through adjacent apertures 20 in the portion 19 of the bottom flange 17 and then upset, as shown in Figure 7.

In Figure 10 there is shown another form of holding plate, wherein the outer ends of the plate are provided with lips 26 adapted to be snapped over the portion 19 of the bottom flange 17. If desired, the lips 26 of the plate 22 may be indented, as at 27, to facilitate this action, and the portion 19 of the bottom flange 17 may be provided with slots (not shown) to receive the indented portions 27 of the lips 26.

From the above description it will be seen that I have provided a simple and effective means for easily attaching covering material to a frame member without necessitating sewing, at the same time compensating for the bunching of the covering material when the frame has curved corners.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. In a hand bag, a frame member comprising an inner side wall provided with top and bottom flanges, the top flanges having a flange bent downwardly parallel to the inner side wall, and covering material positioned be-

tween the flanges, the bottom flange having a portion bent upward to present an outer side wall to securely hold the covering material in the frame member.

2. In a hand bag, a frame member comprising an inner side wall provided with top and bottom flanges, the top flanges having a flange bent downward parallel to the inner side wall, and covering material positioned between the flanges, the bottom flange having a portion bent upward to present an outer side wall to securely hold the covering material in the frame member, said bottom flange having a plurality of holes to facilitate bending of said portion.

3. In a hand bag, a frame member comprising an inner side wall provided with top and bottom flanges, the top flange having a flange bent downward parallel to the inner side wall, said frame having curved corners, covering material positioned between the flanges, the bottom flange having a portion bent upward except at the curved corners of the frame member to present an outer side wall to hold the covering material in the frame, and plates curved to coincide with the curvature of the curved corners, said plates being positioned in the frame at the corners and attached to the outer side wall to prevent bunching of the covering material at the corners.

4. In a hand bag, a frame member comprising an inner side wall having outwardly directed top and bottom flanges, said frame member having curved corners, covering material positioned between the flanges, the bottom flange having a portion bent upward except at the curved corners to present an outer side wall to hold the covering material in the frame, and curved flat plates positioned over the material at the corners, said plates preventing bunching of the material and enabling an easy and neat assembly at the corners.

5. In a hand bag, a frame member comprising an inner side wall having outwardly directed top and bottom flanges, said frame member having curved corners, covering material positioned between the flanges, means on the bottom flange to hold the covering material in the frame, and curved flat plates positioned in the curved corners to prevent bunching of the material at the corners.

6. In a hand bag, a frame member comprising an inner side wall provided with top and bottom flanges, the top flange having a flange bent downward parallel to the inner side wall, said frame having curved corners, covering material positioned between the flanges, the bottom flange having a portion bent upward except at the curved corners of the frame member to present an outer side wall to hold the covering material in the frame, plates curved to coincide with the curvature of the curved corners, said plates

being positioned in the frame at the corners and having holes in their extremities, said bent up portions of the bottom flange having elongated slots adjacent the ends of the curved plates, and means passing through the slots and the holes in the plates to attach the plates to said apertured portions.

7. In a hand bag, a frame member comprising an inner side wall provided with top and bottom flanges, the top flange having a flange bent downward parallel to the inner side wall, said frame having curved corners, covering material positioned between the flanges, the bottom flange having a portion bent upward except at the curved corners of the frame member to present an outer side wall to hold the covering material in the frame, and plates curved to coincide with the curvature of the curved corners, said plates being positioned in the frame at the corners, each plate having lips at its ends adapted to be snapped over adjacent portions of the bottom flange to securely hold the plate in position.

25 This specification signed this 21st day of January, 1932.

WILLIAM C. HIERING.
